UNITED STATES PATENT OFFICE.

CARL J. MELLIN, OF RICHMOND, VIRGINIA, ASSIGNOR TO THE RICHMOND LOCOMOTIVE AND MACHINE WORKS, OF SAME PLACE.

COMPOUND ENGINE.

SPECIFICATION forming part of Letters Patent No. 536,640, dated April 2, 1895.

Application filed April 11, 1894. Serial No. 507,196. (No model.)

To all whom it may concern:

Be it known that I, CARL J. MELLIN, a citizen of the United States, and a resident of Richmond, in the county of Henrico and State 5 of Virginia, have invented certain new and useful Improvements in Compound Engines, of which the following is a specification.

My invention consists in improvements in intercepting valves for temporarily working 10 high steam direct in both cylinders of a compound engine at starting, whereby the valve will be automatically operated for changing from one to the other condition, and pressure will be duly limited in the low pressure 15 cylinder for safety and practicability, as hereinafter described reference being made to the accompanying drawings, in which—

Figure 1, is a longitudinal sectional elevation of my improved intercepting valve with 20 the valve open as when working compound. Fig. 2, is a similar section with the parts in the positions as when working steam direct in both cylinders, and Fig. 3, is a similar section with the parts in the positions as when 25 working steam direct in both cylinders, and with the live steam admission valve closed by overbalancing pressure in the low pressure cylinder to prevent excessive pressure therein.

The valve case *a*, is to be connected at any 30 suitable position in the passage for the exhaust steam from the high pressure cylinder to the low pressure cylinder so that the steam is received in the chamber *b*, between which and the outlet *c* to the low pressure cylinder 35 is the intercepting valve *d* arranged to be opened automatically by the pressure in receiver *b* for the flow of the steam into the low pressure cylinder when working in the compound system. On the back of this valve *d*, 40 is a hollow stem or sleeve *e*, fitted to slide in the bored cylinder *f* to which live steam is admitted at *g* from the pipe *h* always open to live steam when the throttle valve is open, said sleeve *e*, having a shoulder *i* that is sub- 45 ject to live steam pressure for closing valve *d*, the rest of the sleeve *e* and the corresponding part *f'* of the sleeve cylinder being of smaller size to enable the steam to have impelling effect on the shoulder. The outer end 50 of the smaller part of the sleeve is open to the atmosphere.

At *k* are ports so placed that they communicate with the steam space *g*, when valve *d* is closed and admit live steam to the interior of the sleeve. At *l*, are other ports in said sleeve 55 so placed that they open communication with the low pressure cylinder at the extremity of sleeve cylinder *f*, when said valve *d* is closed, and between these ports *k* and *l*, is a piston valve *m*, which has a seat at *n*, and closes communication between said ports to shut off live steam when pressure rises too high in the low pressure cylinder, said valve being then overbalanced by the cylinder pressure on its other end having communication therewith through 60 other ports *o*, of said sleeve, so that this valve automatically controls the pressure of live steam in the low pressure cylinder. The stem *p*, of this valve extends out through part *e'* of the sleeve and has a nut *q*, between which 65 and the end of the sleeve a coiled spring may be applied to graduate the action of the valve. It will be seen that through this provision of separate means for closing the valve *d*, and for admission of the steam each may be better adapted as to area of steam space for its 70 particular purpose, whereby less area being required on shoulder *i* for closing the valve *d* only, than if for admission of the steam that way also, the said valve will close more gently 75 and with less damage by hammering the seat.

The valve *d* closes in a recess *d'* the depth of which is to be such that the said valve enters the mouth of the recess at the moment ports *l* open at the end of cylinder *f*, and thus 80 prevents escape of live steam into the receiver during the rest of the movement of valve *d*, in closing. The sleeve *e e'* is made separately 85 from valve *d* and is bolted thereto.

At *s*, I represent the cylinder, and at *t*, the piston of the dash-pot employed to check the closing of the valve *d*, and for exhausting receiver *b*, when the valve *d* is closed, and live steam is to be used directly in both steam cylinders, the ports *u* opening said exhaust 95 after passing the head of the piston, but this is the subject of claims in another application for a patent and is not claimed herein.

When the engine is running the pressure of exhaust steam in the receiver on valve *d* 100 overbalances the pressure of live steam on shoulder *i*, and opens said valve. The engine

then works by the compound system, but when there is little or no pressure of exhaust steam in the receiver, the live steam pressure on shoulder *i* closes valve *d*, and opens admission 5 for live steam through openings *k* to the reducing valve *m*, which in turn opens and admits live steam to the low pressure cylinder. Then both cylinders work with live steam.

The hollow stem *e*, *e'* of the intercepting 10 valve is bored in three different sizes. The piston *m* of the live steam admission and reducing valve is arranged in the larger portion of the bore and closes on the seat *n*, which is intermediate of the ports *k*, *l*, and is 15 a ground joint for tight closing. The portion of the bore of said sleeve and the shoulder *z* together with the intermediate section *p'* of the stem of valve *m*, determines the amount of reduction of the live steam admitted, and 20 the ratio between the smallest and the largest bores determines the steam pressure in the low pressure cylinder in running with live steam direct in both cylinders. The intermediate bore in the live steam passage to the 25 low pressure cylinder, in which the intermediate portion *p'* of the reducing valve stem fits being reduced to the smallest practicable limits, affords sufficiently large area for the steam in a bore of comparatively small size.

30 The shoulder *i* on which the live steam acts to close the intercepting valve never passes out of the end of the cylinder *f*, and consequently there is no other admission for live steam except through the reducing valve.

35 When the intercepting valve is open, piston valve *m* passes ports *l* to its seat, and shoulder *i* passes ports *k* to its seat *j*, and the live steam ports *k* are shifted past shoulder *j* into the smallest part of the bore of cylinder *f* thus 40 shutting off the supply of live steam to the reducing valve, so that the reducing valve being closed by receiver pressure, the live steam and the steam from the receiver are effectually shut off by ground valve seats, the former by the shoulder *i* of the hollow stem of the intercepting valve and the latter by the shoulder of the reducing valve.

I claim—

1. In a compound engine, the combination 50 with the intercepting valve in the steam receiver between the high and low pressure cylinders, of the sleeve having the exterior shoulder subject to live steam for closing the valve, and the admission ports for the live steam to the low pressure cylinder through the sleeve, said valve adapted to cut off communication between the high and low pressure sides of the receiver at or before the opening of said live steam admission ports substantially as described.

2. In a compound engine, the combination 55 with the intercepting valve in the steam re-

ceiver between the high and low pressure cylinders, of the sleeve having the shoulder subject to live steam for closing the valve, and 65 the admission ports for the live steam to the low pressure cylinder; and the valve in said sleeve subject to overbalancing effect of excessive pressure in the low pressure cylinder to automatically shut off the live steam substantially as described.

3. In a compound engine, the combination 70 with the intercepting valve in the steam receiver between the high and low pressure cylinders, of the sleeve having the shoulder subject to live steam for closing the valve, and the admission ports for the live steam to the low pressure cylinder; and the valve in said sleeve to shut off the live steam, said sleeve also having the ports behind said valve and 75 said valve adapted to be overbalanced by excessive pressure thereto admitted behind it, and to thereby automatically shut off the live steam substantially as described.

4. The combination with the hollow stem of 80 the intercepting valve having the differential bores of the extremities, the steam ports *k*, *l*, and the seat *n*, intermediate of said ports, of the reducing valve having the small and larger 85 extremities, and the intermediate connecting stem, substantially as described.

5. The combination with the hollow stem of 90 the intercepting valve having the differential bores of the extremities and intermediate portion, the steam ports *k*, *l*, and the seat *n*, 95 intermediate of said ports, of the reducing valve having the small and large extremities and the intermediate connecting stem substantially as described.

6. The combination with the hollow stem, of 100 the intercepting valve having the shoulder *i*, the ports *k* and *l*, and *o*, and shoulder *n*; of the cylinder *f* having the steam space *g*, and the seat *j*, and the reducing valve having the 105 larger and smaller extremities, and adapted to close on the seat *n*, substantially as described.

7. The combination with the intercepting valve, of the hollow stem of said valve having the ports *k*, *l*; the cylinder *f* for said stem 110 having the steam space *g* and seat *j*, and the reducing valve located in said stem, said sleeve and cylinder adapted for the ports *k* to cut off the steam space, and the reducing valve adapted to cut off ports *l*, when the intercepting valve opens substantially as described.

Signed at Richmond, in the county of Henrico and State of Virginia, this 4th day of April, A. D. 1894.

CARL J. MELLIN.
